NEIL G. HAYES, OF BRIDGEPORT, CONNECTICUT, ASSIGNOR OF ONE-HALF TO ADELBERT R. AURAY, OF BRIDGEPORT, CONNECTICUT

PUSH-BUTTON HOUSING

Application filed February 17, 1928. Serial No. 254,944.

This invention relates to electrical push button constructions, and particularly to the housing enclosing the electrical mechanism, its object being to form the housing and all parts thereof for supporting the button and electrical mechanism of a single piece of sheet metal, thus reducing the number of parts and materially cheapening the cost of construction.

10 Referring to the accompanying drawing wherein the same characters of reference indicate like parts throughout the several views—

Figure 1 represents an elevation of the housing and its push button—

15 Figure 2 is a central sectional elevation of an integrally constructed housing—

Figure 3 is a broken view of the exterior part of the one piece housing and a full view of a depending interior portion—

20 Figure 4 is an interior plan view of the housing—

Figure 5 is a bottom plan view of the housing equipped with the electrical mechanism—

25 Figure 6 is a sectional view of the housing and a full view of the electrical mechanism, and

Figure 7 is an enlarged broken sectional view of the housing and its integrally depending features.

The one piece sheet metal housing consists of the shell 1 having the inwardly projecting flange 2 and the opening 3 through which projects the body 4 of the push button, while 35 the flange 5 of the button is normally held against the underside of the flange 2 by the conventional contact springs 6.

The depending shell 7 embraces the button and the major part of the electrical mechanism with the base 8 resting against the end of the shell 7, and is held there by the integrally projecting clips 9, the conventional electrodes 8a being secured to the base 8. The depending member 7 thus forms a supporting 40 housing for the electrical mechanism. The member 7 is first drawn down from the central part of the shell 1 of tubular form and its sides upset to form an inwardly projecting fold for the push button support 2, as shown 45 in Fig. 7.

The prevailing type of push button housing constructions carrying the necessary electrical equipment, are made of sheet metal, and comprise a plurality of assembled parts to support said equipment, thus materially increasing the cost of production.

55 In the present improvement, a single piece of sheet metal is shaped, by proper tools, not shown, to form the outer shell 1, and the internal support for the electrical equipment, 60 thus making a neat, compact, and cheap construction to which the electrical mechanism is readily attached.

Certain type of push button constructions 65 are sunk below the surface, but the type herein shown contains the electrical equipment and are supported on the surface and project above the same.

The gist of the invention resides in a push button housing, having a central push button 70 opening, a retaining support for the button with a support for the electrical mechanism depending therefrom, all made of a single piece of sheet metal.

75 While modified changes could be made as to the general shape of the one piece housing construction, any such changes that includes a retaining support for the button and a support depending therefrom for electrical mechanism, must necessarily be considered 80 the equivalent of my construction.

Having thus described my invention what I claim is:—

85 A push button construction formed from a single piece of sheet metal, comprising an outer shell having a central and inwardly depending tubular portion, said tubular portion being adapted to embrace and support the electrical mechanism, and an inwardly projecting push button support formed by folding and upsetting the metal of said tubular portion.

90 In testimony whereof I affix my signature.
NEIL G. HAYES.
